STORAGE POD FOR A TRAILER TOP OR THE LIKE

Robert L. Brison, Glendora, and Albert J. Luirette, Santa Ana, Calif., assignors to Inca Plastics, Inc., Santa Ana, Calif.

Filed June 19, 1974, Ser. No. 480,995

Term of patent 14 years

Int. Cl. D3—02

U.S. Cl. D87—1 R

Fig. 1

Fig. 2

Fig. 3

Fig. 5

Fig. 6

Fig. 4

FIG. 1 is a top perspective view of a storage pod for a trailer top or the like embodying our new design;

FIG. 2 is a side elevational view thereof;

FIG. 3 is an enlargement of FIG. 2;

FIG. 4 is a front elevational view of the storage pod for a trailer top or the like of FIG. 1;

FIG. 5 is a top plan view thereof; and

FIG. 6 is a bottom plan view.

We claim:

The ornamental design for a storage pod for a trailer top or the like, substantially as shown.
